UNITED STATES PATENT OFFICE.

ANTHONY SNELL, OF ROCHESTER, NEW YORK.

BRIDGE-WALL.

SPECIFICATION forming part of Letters Patent No. 369,564, dated September 6, 1887.

Application filed May 20, 1887. Serial No. 238,813. (No model.)

To all whom it may concern:

Be it known that I, ANTHONY SNELL, of Rochester, in the county of Monroe and State of New York, have invented a new and useful

5 Improvement in Bridge-Walls, which improvement is fully set forth in the following specification and shown in the accompanying drawings.

The object of my invention is to produce an 10 improved bridge-wall for a steam-boiler furnace, the same being hereinafter fully described, and more particularly pointed out in the claim.

Referring to the drawings, Figure 1 is a side 15 elevation of a portion at the front end of a furnace for a horizontal steam-boiler, a part of the side wall being broken out to uncover the bridge-wall, the latter being vertically sectioned at the top, as on the dotted line *x* in Fig. 2, and at the bottom, as on the dotted line *y*; Fig. 2, a front elevation of the bridge-wall, the side walls of the furnace, the boiler, and grate being vertically sectioned, as on the dotted line *z* in Fig. 1, a part of the front wall 20 of said bridge-wall being removed to expose the cavity therein; Fig. 3, a side elevation of a furnace, showing another form of bridge-wall, the view being similar to that shown in Fig. 1, a part of the side wall being broken out and the bridge-wall being in part vertically sectioned, as on the dotted line *x'* in Fig. 5, and viewed as indicated by the arrow pointed thereon; Fig. 4, a sectional elevation of a portion of the bridge-wall, seen as in Fig. 3 and 25 sectioned by the same plane, drawn to a larger scale to better show the damper, the latter being shown in two positions by full and dotted lines; Fig. 5, a transverse section of the furnace and other parts, taken as on the dotted line *y'* in Fig. 3, and viewed as indicated by the arrow pointed thereon, the figure showing a view of the rear side of the bridge-wall; Fig. 6, a vertical section of a portion of the bridge-wall, seen in the direction in which Figs. 3 30 and 4 are seen, said wall and a portion of a grate being sectioned as on the dotted line *z'* in Fig. 5; and Fig. 7, a view of the bridge-wall and parts associated therewith, seen as indicated by arrow *x''* in Fig. 5, the walls being horizontally sectioned, as on the dotted line *y''* in Fig. 5.

Referring to the parts, A is the furnace for

a horizontal steam-boiler, B, C being the side walls of the furnace, D the grate, and E the cast-iron front thereof, all substantially of common form. 55

F is the transverse bridge-wall at the rear of the furnace, the form of which wall constitutes the novelty of my invention. The essential feature is that the wall is hollow vertically, for the purpose of admitting air with its full supply of oxygen to the flame from the fire, for the double purpose of effecting a more complete combustion and of driving the flame against the boiler-sheets. Two forms of my 60 improved bridge-wall are shown. That shown in Figs. 1 and 2 is the form I build when a new boiler, arch, or furnace is constructed. The form shown in Figs. 3 to 7 represents the bridge-wall when built into an old furnace or 70 boiler arch. The combustion being more perfect when my hollow bridge-wall is used enables me to shorten up or reduce the grate-surface. On this account, when I build a new furnace I use shorter grates, as shown in Fig. 75 1, and when I build a new bridge-wall in an old arch I build it upon the ends of the grates, as shown in Fig. 3, thus reducing the length of the original grate-surface.

The bridge-wall is built with fire-brick and 80 formed with an internal vertical cavity, *a*, which, in the form shown in Fig. 1, extends from the bottom to the top of the bridge-wall, while in the form shown in Fig. 3 it extends only part way of the height of said wall, the 85 latter being made solid above and below said cavity. In either case the openings of the cavity are respectively below and above the level of the grate. In Figs. 1 and 2 the inlet-opening *b* for the air below the grate is shown 90 formed with an arched top, free passages being given to the air up through the bridge-wall to the flame beneath the boiler. The inflowing air passes through draft-openings in the iron front E of the furnace and through the arch-way *b*. (Plainly indicated by arrows.) 95

In the form shown in Fig. 3 the opening *b* below the grate is a simple rectangular opening of suitable size; or it may be a horizontal row of openings formed by omitting alternate 100 bricks from the front part of the bridge-wall when the latter is being built. In this form also the cavity *a* opens out into the space G in the rear of the bridge-wall through openings *c*,

formed in the rear part of said bridge-wall. From these openings *c* the air flows upward along the rear surface of the wall to the flame beneath the boiler, as in the case of the other form described.

5 In the form shown in Fig. 3 the air entering the opening *b* flows upward through between the grate-bars and out at the openings *c*, (clearly indicated by arrows in Fig. 4,) said air primarily entering beneath the grate through the iron furnace-front, as in the first instance.

I sometimes find it convenient, in addition to the openings *c*, to add vertical air-passages *d* to the rear side of the bridge-wall, forming 15 said passages so as to communicate by means of openings *e* with the cavity *a*, as clearly shown in Fig. 6. These air-passages tend to direct the currents of air more certainly upward to the flame.

20 A simple damper, *f*, in the form of a flat bar placed horizontally in the cavity *a* upon bearings at its respective ends, serves to regulate the flow of air upward through the bridge-wall. A handle, *G*, upon the outside of the 25 side wall of the furnace, rigid with the damper, enables the attendant to adjust the damper as may be required.

The fresh air from without, being conducted into the flame at the top of the bridge-wall,

supplies oxygen for a more complete combustion of the accompanying smoke or unburned carbon, thus adding to the intensity of the heat under and around the boiler. Besides, the currents of air rushing upward tend to drive the flame more closely against the boiler-sheets, 35 and thus increase the generation of steam within.

The bridge-wall, as shown in Fig. 1, is formed with a horizontal ledge, *h*, along its front face, projecting forward to receive and hold the 40 rear ends of the grate-bars. The forward ends of said bars rest on a similar ledge, *i*, cast in the usual manner on the inner face of the iron front *E*.

What I claim as my invention is—

45 In combination with a steam-boiler furnace and fire-grate therefor, a hollow transverse bridge-wall formed with openings in the front side thereof, below said grate, communicating with the cavity in said bridge-wall, and vertical air-passages on the rear side of said bridge-wall, said passages communicating with said cavity within said bridge-wall, substantially as shown and described.

ANTHONY SNELL.
